UNITED STATES PATENT OFFICE

MARTIN A. MIRANDA, OF MIDDLE VILLAGE, NEW YORK, ASSIGNOR TO HOLMES ELECTRIC PROTECTIVE COMPANY, OF NEW YORK, N. Y., A CORPORATION OF NEW YORK

ALARM SYSTEM

Application filed July 30, 1925. Serial No. 46,942.

This invention relates to alarm systems, and particularly to burglar alarm systems.

It is an object of the invention to provide a new and improved burglar alarm system which comprises a means for testing a system under various conditions.

The invention is particularly adapted for use in an alarm system in which tests may be made at a central station over lines extending to subscribers' stations at a potential common to all lines regardless of their respective lengths.

The invention relates to a normally closed protective circuit which includes a means for partially unbalancing one of the windings of a differential relay at a subscriber's station in such a manner that the relay is not responsive to a normally applied low potential, but is responsive to a high potential which is impressed on the line for testing purposes.

More specifically, the invention relates to the arrangement of a shunt resistance placed across one of the windings of a differential relay whereby the relay which is thus rendered partially unbalanced remains inoperative in the normally closed protective circuit when the normally applied low potential is on the line, but with an increase in the potential the relay becomes operative and closes an operating circuit to a changer magnet which thereupon operates to bring about a desired change in the protective circuit for making a test of the condition of the system.

Other features and advantages of the invention will appear from a consideration of the following description taken in conjunction with the accompanying drawing which shows a diagrammatic view of a circuit embodying the invention.

Referring to the drawing, the main circuit includes a galvanometer 1, a low voltage battery 2, a two-way key 3 of the non-locking type located at the central office, a signaling key 4, an alternating current ringer 5, a changer magnet 6, a differential relay 7, a switch 8 arranged to set the alarm system for either a day or night period, a set of contact devices 9 for the doors and windows of the protected premises, a protective wiring network 10 for doors, windows and walls, ad-

justable resistances 11 and 12, a fixed resistance 13 serving as a shunt for one of the windings of the differential relay, and a condenser 14 located at the protected premises of a subscriber. The galvanometer is furnished for the purpose of informing the operator at the central office the condition of the subscriber's line and for controlling the operation of a drop signal and a buzzer at the central office, as will hereinafter be explained. The low voltage battery 2 is provided for the normal operation of the system and the two-way key 3 is employed as a means for changing the system from one condition to another so as to test the line under each, and signaling the subscriber the results of the testing so that should any defects exist in the system the trouble may be remedied before the premises are closed for the night. The signaling key 4 provides the subscriber with means for operating galvanometer 1, drop 34, and buzzer 35 at the central office, thereby informing the operator that the premises are about to be closed for the night and that therefore it is time to make the necessary test to see if the system is in operable condition.

The ringer 5 is responsive to the operation of the key 3 when switched into the ringing position. The changer magnet 6 is operated when key 3 is switched into its testing position to substitute a high voltage battery 15 in place of the battery 2. The relay 7 being of a differential type has two windings which are equal in effective ampere turns and resistance so that when the current traverses all the loops of the protective circuit the magnetic field of one winding neutralizes the magnetic field of the other and the relay does not operate. When one winding however is shunted either by design or an unauthorized attempt to tamper with the protective circuit the relay is permitted to operate, thereby causing to operate the galvanometer 1, the drop 34, and the buzzer 35 at the central office. The differential relay differs from the ordinary type in that its right-hand winding is shunted by a resistance and it is thus rendered partially unbalanced, but not sufficiently unbalanced as to cause operation of the drop signal and buzzer at the central office, while the normally

applied low voltage battery is connected to the protective circuit.

The variable resistances 11 and 12, herein-after referred to as the auxiliary and changer coils, respectively, are provided as a means for providing a definite current flow in the particular subscriber's line; and the fixed resistance 13 is the shunt referred to above as being placed across the right-hand winding 10 of relay 7, and is furnished for the purpose of providing an artificial error in the right-hand winding to effect a partial unbalance, but this error, or unbalance, is not of sufficient magnitude to cause the relay to operate when the low potential is normally applied to the line. When the potential is increased, the unbalance is likewise increased and the difference in the current flow through both windings of the relay, is raised to such an extent as to cause the relay to operate. The differential relay is arranged to be operated momentarily inasmuch as the high potential is applied by key 3, which is of the non-locking type, but it will be of sufficient 20 duration to insure the positive operation of the changer magnet, as is particularly desired on long lines. The key 3 is so arranged that it breaks the line for a brief interval when it is released to shift from high voltage battery 25 15 to low voltage battery 2. This break permits the armature of the relay 7 at the subscriber's station to operate thus including the network in the line again. The purpose of operating the relay 7 is to shunt out the network momentarily to allow current at full 30 strength to flow through the magnet 6. In this manner the operation of the magnet is always insured.

When the system is set for its night period, 40 switch 8 is in the position shown in the drawing and the protective circuit may be traced from the negative pole of battery 2, through the galvanometer 1, inner right-hand contacts of key 3, conductor 16, normal contacts of key 4, through ringer 5, through the winding of changer magnet 6, through the left-hand winding of relay 7, next to the uppermost contact of switch 8, left-hand contacts of contact devices 9, lower innermost contact of switch 8, lower arm of network 10, through the right-hand winding of relay 7, through the variable resistances 12 and 11, upper arm of network 10, right-hand contacts of contact devices 9, conductor 50 17, inner left-hand contacts of key 3 to ground. This circuit places the system in its normal position, or what is commonly called a high-coil condition, that is, both the auxiliary and changer coils, connected in series, 55 are included in the circuit. Should any one attempt to make an unlawful entry into the protected premises during the night period by opening any of the contact devices or disturbing the protective network, the normally balanced galvanometer associated with 60 65

the line extending to the entered premises would be deenergized and the galvanometer needle would, therefore, deflect to its left contact to close an alarm operating circuit 33 which operates the visible signal 34 and audible signal 35 at the central office, but should any of the networks in doors or windows, for instance, be short circuited in an attempt to maintain the protective circuit closed so that a door or window might be opened without breaking the circuit, the change in resistance in the protective circuit due to the shorting out of the network would result in an increased flow of current through the galvanometer, the movement of the pointer over to the high contact and the operation of the drop signal and buzzer at the central office.

When the system is set for its day period so that the doors and windows may be opened 85 without operating an alarm, the switch 8 is set in its alternate position and the circuit for this period may be likewise traced from the central office, conductor 16, through ringer 5, upper innermost contact of switch 8, through the lower arm of network 10, lowermost contact of switch 8, through the resistance 11 and the upper arm of network 10, next to the lowermost contact of switch 8, 90 conductor 17, back to the central office. 95

The main circuit during the closed period is arranged to be tested by the operator at the central office for several conditions, such as high-coil, when both the auxiliary and 100 changer resistance coils 11 and 12, respectively, are included in the circuit, low-coil, when the changer coil 12 is shunted, and short, when the protective portion of the main circuit is short-circuited by the operation and locking of relay 7. These three 105 conditions provide means for the purpose of enabling the operator to determine the current strength of the circuit when the resistance of said circuit is varied, the high-coil condition representing the normal stage, 110 low-coil condition representing the stage in which all loops of the circuit are tested, and the short circuit condition representing a 115 test for the proper operation of the differential relay.

The galvanometer which is individual to each subscriber's line is arranged to show a test reading for each of the three coil changes and should there be any discrepancies in any of these readings for a subscriber's line under test, the operator will know that there is trouble on the line and the necessary steps can be taken to remedy it. The readings for the high and low coil 120 conditions of all lines are approximately the same, inasmuch as the varying lengths of the lines may be compensated for by adjusting the resistances, such as auxiliary coil 11 and changer coil 12, which are individual to each 125 subscriber's line. 130

It should be understood that the subscriber's circuit is known to have a certain resistance when all the elements including the changer coil 12 are in circuit and therefore the operator in making the high-coil test looks at the galvanometer to see if this resistance is present. Then the operator knows what the resistance of the circuit should be with the changer coil 12 short-circuited, that is, the resistance of the loops, and in making the low-coil test observes the galvanometer to see if the reading is correct. The third test is merely to check up on the operation of the differential relay. The operator knows what the galvanometer should read when the network is shorted by relay 7 and in making the last test observes the reading of the galvanometer to see if it corresponds to the known resistance. If the galvanometer on these readings does not deflect predetermined distances the operator knows that some part of the circuit is defective or has been tampered with and takes measures accordingly.

The changer magnet which effects the various coil standing changes is arranged to operate when the key 3 at the central office connects the high voltage battery to the main circuit. The high voltage battery which is impressed on the line causes the operation of the differential relay, as hereinbefore stated to insure the operation of the magnet. This magnet is equipped with an armature 18 which is integral with a pivotal bar 19, extending parallel to and for the full length of the core of said magnet. At the free end of bar 19 a pin 20 is fixedly attached for the purpose of providing a supporting means for a U-shaped member comprising two separately mounted legs 21 and 22. The legs are pivotally arranged on the pin 20 and are located thereon sufficiently apart to permit a short coil spring 23 to be mounted between them. The ends of the spring 23 are detachably secured to lugs 24 and 25 on legs 21 and 22, respectively, so that the tension in the spring tends to draw the legs together. Disposed between the free ends of legs 21 and 22 and in engagement therewith is a ratchet wheel 26, which is loosely mounted on the magnet supporting frame (not shown). The free end of leg 21, being hook-shaped, is adapted to engage the teeth on the ratchet wheel on one side and the free end of leg 22, being pointed, is adapted to engage the teeth on the opposite side. When the armature 18 is attracted the legs 21 and 22 are drawn downward and the hook-shaped leg 21 causes the ratchet wheel to rotate one step in a counter-clockwise direction, and when the armature is released the legs 21 and 22 return to normal and the pointed leg 22 which has become locked with the ratchet wheel on its downward movement rotates the wheel further in a counter-clockwise direction another step, so that with each rotation and release of arma-

ture 18 the ratchet wheel rotates in two steps or through the distance of one tooth. Fixedly attached to the ratchet wheel and concentrically arranged thereon is a cam 27 so fashioned as to provide three sets of cam surfaces, each set consisting of three surfaces differently positioned radially, such as top, middle and bottom surfaces corresponding to the three coil conditions of the system, namely, high-coil, low-coil and short, as hereinbefore described. Cooperating with cam 27 to close the necessary circuits for the three conditions in the order mentioned is a set of spring members 28, 29 and 30, which are fixedly mounted on the magnet supporting frame (not shown), the middle member 28 being arranged to effect a contact with either of its associated members 29 and 30 and further arranged to extend beyond its associated members to engage the surfaces of cam 27, the point of engagement being insulated. When the middle member is in engagement with the middle surface of the cam, no contact with the associated members 29 and 30 is effected and the system is normal, or, what is commonly called, high-coil standing, and both coils 11 and 12 are included in the main protective circuit. When the ratchet wheel is rotated through two steps in a counter-clockwise direction, the middle member engages the top surface of the cam and the system is set in a low-coil condition because the middle member closes a contact with member 29, thereby shunting the resistance coil 12 out of the main circuit. The cam is again rotated in two steps and the middle member engages the bottom surface of the cam to close a contact with member 30, which changes the system to a short circuit condition by shunting the right-hand winding of the differential relay and causing the relay to operate and lock, thereby short-circuiting the protective portion of the circuit.

In order to test the system regularly, the closing time for the protected premises is usually selected for such test because at such times a subscriber should be certain that his circuit is in operable condition before he locks his premises. After the subscriber has closed all the circuits of his premises, the switch 8 is operated to its closed position, as shown in the drawing. The subscriber then operates key 4, which operates galvanometer 1 and signals 34 and 35 at the central office to inform the operator that he desires to have his line tested. The operator depresses the non-locking key 3, thereby connecting the high voltage battery 15 to the main circuit. The changer magnet 6 and differential relay 7 operate, but both immediately release. The attraction and subsequent release of the armature 18 causes the cam 27 to move two steps so that the spring 28 engages the top, or low-coil contact. When the spring member 28 engages the top surface

of the cam, a circuit putting the system in low-coil standing is closed, which circuit may be traced from battery, through galvanometer 1, inner right-hand contacts of switch 3, conductor 16, normal contact of key 4 through ringer 5, winding of magnet 6 and left-hand winding of relay 7, next to the uppermost contact of switch 8, left-hand side of contact devices 9, lower innermost contact 5 of switch 8, lower arm of network 10, through the right-hand winding of relay 7 and shunt resistance 13 in parallel, contact members 28 and 29, through the auxiliary coil 11, upper arm of network 10, right-hand side of contact devices 9, conductor 17 to ground on the upper inner left contact of key 3. If the main circuit is closed through all the loops, the galvanometer needle will deflect and show a definite change, but if this current change 10 is not indicated, the operator knows that some part of the circuit is open or defective. When the low-coil standing registers satisfactorily the operator again depresses her key 3 to test the circuit for short standing 15 and the second operation of this key likewise energizes magnet 6 and relay 7. The operation and release of the magnet armature 18 moves the cam one more step to bring the bottom notch of the cam into engagement 20 with spring member 28. This engagement causes a closure to be made between contact members 28 and 30 and shunts the right-hand winding of differential relay 7. When the low voltage battery is again brought into the 25 circuit differential relay 7 will lock up and shunt out the protective circuit, the circuit which causes the shunting circuit to close being traceable from low voltage battery 2, galvanometer 1, inner right-hand contacts of key 3, conductor 16, normal contacts of key 4, through ringer 5, magnet 6 and left-hand winding of relay 7, next to the uppermost contact of switch 8, left-hand side of contact devices 9, lower innermost contact of switch 40 30, lower arm of network 10, contact members 30 and 28, through coils 12 and 11, upper arm of network 10, right-hand side of contact devices 9, conductor 17, inner left contacts of key 3 to ground. The locking circuit for relay 7 shunts out the attachments, 45 protective network, right-hand winding of relay 7, fixed resistance 13 and variable resistance coils 11 and 12, and the increased current causes a wide deflection of the galvanometer needle, which deflection indicates 50 to the operator that a large current change is effected and that the changer magnet and differential relay together with the signal equipment in the central office are in operable condition. After the galvanometer needle 55 has made this wide deflection, the operator depresses her key again into the test position and the cam moves two steps so that the spring member 28 engages the middle 60 surface of the next set on the cam and the 65

system is, therefore, restored to its normal, or high-coil, condition. When the system is restored to normal the operator depresses her key 3 to ringing position so as to operate ringer 5 an arbitrary number of times to inform the subscriber that the system operates satisfactorily and that he may lock his premises. 70

What is claimed is:

1. An alarm system comprising a normally closed protective circuit, a current measuring device therein, protective networks and contact devices in said circuit, a low voltage source of current normally included in said normally closed circuit, a high voltage source 75 of current and means to disconnect said current measuring device and said low voltage source of current from said normally closed circuit and to connect in to said normally closed circuit said high voltage source of current, a magnet included in said circuit, means operated by said magnet to change the resistance of said circuit whenever the current in said circuit is increased by including the high voltage source in the circuit, sensitive relay means including a coil included 80 in said circuit, said relay means including contacts which are closed when the high voltage source is connected to said circuit and circuit means associated with said contacts 85 and network to insure the operation of said magnet by short circuiting from said system said protective contact devices and network when the contacts are closed. 90

2. An alarm system comprising a central 100 station, a substation, and a normally closed circuit connecting said stations, a current measuring device, protective contacts and networks in said normally closed circuit, said circuit measuring device and alarm devices 105 operated thereby located at said central station, a low voltage source of current normally included in said normally closed circuit, a high voltage source of current and means for connecting said high voltage source into said 110 normally closed circuit in place of said low voltage source, a magnet included in said circuit, means operated by said magnet to change the resistance of said circuit whenever the current in said circuit is increased by including the high voltage source in the circuit, a sensitive relay means including a coil included in 115 said circuit, said relay means including contacts which are closed when the high voltage source is connected to said circuit and circuit means associated with said contacts and network to insure the operation of said magnet by short circuiting from said system said protective contacts and network when the contacts are closed. 120

3. An alarm system comprising a central station, a substation, a normally closed circuit including a current measuring device, protective contact devices and networks connecting said stations, alarm devices at the 125 130

central station operated from the substation, a source of low potential normally included in said closed circuit, a source of high potential, and means to connect the high potential source into said closed circuit in place of the low potential source, a magnet included in said circuit, means operated by said magnet to change the resistance of said circuit whenever the current in said circuit is increased by including the high voltage source in the circuit, sensitive relay means including a coil included in said circuit, said relay means including contacts which are closed when the high voltage source is connected to said circuit and circuit means associated with said contacts and network to insure the operation of said magnet by short circuiting from said system said protective contact devices and network when the contacts are closed.

4. An alarm system comprising a central station, a substation, alarm devices at the central station, protective contacts and networks at the substation connected to said devices to cause the operation of the alarm devices, and a normally closed circuit connecting said stations, a source of low potential for said normally closed circuit, a source of high potential for making tests of the system, and means to connect said high potential source into the normally closed circuit in place of said low potential source, a magnet included in said circuit, means operated by said magnet to change the resistance of said circuit whenever the current in said circuit is increased by including the high voltage source in the circuit, sensitive relay means including a coil included in said circuit, said relay means including contacts which are closed when the high voltage source is connected to said circuit and circuit means associated with said contacts and network to insure the operation of said magnet by short circuiting from said system said protective contacts and network when the contacts are closed.

5. An alarm system comprising a central station, a substation, alarm devices at the central station, protective contacts and networks at the substation connected to said devices to cause the operation of the alarm devices, and a normally closed circuit connecting said stations, a source of low potential for said normally closed circuit, a changer magnet included in said normally closed circuit to make changes in the resistance of said circuit for making tests of the system, a magnet including in said circuit, means operated by said magnet to change the resistance of said circuit whenever the current in said circuit is increased by including the high voltage source in the circuit, sensitive relay means including a coil included in said circuit, said relay means including contacts which are closed when the high voltage source is con-

nected to said circuit and circuit means associated with said contacts and network to insure the operation of said magnet by short circuiting from said system said protective contacts and network when the contacts are closed.

In witness whereof, I hereunto subscribe my name this 13 day of July A. D., 1925.

MARTIN A. MIRANDA.
